UNITED STATES PATENT OFFICE.

ABRAHAM COTTRELL, OF LANSING, MICHIGAN.

REIN-HOLDER.

SPECIFICATION forming part of Letters Patent No. 364,336, dated June 7, 1887.

Application filed April 18, 1887. Serial No. 235,223. (No model.)

To all whom it may concern:

Be it known that I, ABRAHAM COTTRELL, a citizen of the United States, residing at Lansing, in the county of Ingham and State of Michigan, have invented certain new and useful Improvements in Driving-Rein Holders; and I do hereby declare that the following is a full, clear, and exact description of the same, reference being had to the annexed drawings, 5 making a part of this specification, and to the letters and figures of reference marked thereon.

Figure 1 of the drawings is a perspective view of my improved driving-rein holder; Fig. 2, a side elevation thereof, and Fig. 3 an 15 end view thereof.

The object of the present invention is to provide a simple and effective device for holding driving-reins; and it consists in the details of construction substantially as shown in the 20 drawings, and hereinafter described and claimed.

In the accompanying drawings, A represents the suitable bracket constructed of metal and provided with means for attaching it to the 25 dash-board, dash-iron, or other convenient portions of a vehicle. In order to attain this end the bracket A is formed with a U-shaped yoke, B, provided with set-screws a, and within the yoke is located a flat metal spring, C, bent in 30 U shape, as shown, whereby the bracket can be conveniently attached to the dash-board.

The yoke B is of sufficient width to protect the dash-iron, and the set-screws a, which adjust the tension of the spring C against the 35 dash-iron, hold the device securely in place. If preferred, the yoke and spring can be dispensed with and a plate with screws substituted, so as to provide means for attaching it to a wooden dash-board; or the device can be 40 so adjusted or means provided to suit any convenient method of attachment to the vehicle. In the means shown the spring C is simply placed within the yoke B, and therefore can be readily removed should it become broken 45 or otherwise injured.

The bracket A is provided with a clamping-arm, D, having a slot, b, at one end, through which passes one end of the spring E. This spring is formed of a flat strip of metal, and has

one end bent around an extension, c, of the 50 bracket, as shown at d; and the opposite end of said spring terminates in a thumb-piece, e, for convenience of operating the spring.

In operation the rein is held between the clamping arm D and spring E, the spring pressing it firmly against the arm, so that it is impossible to slip, the rein being quickly and easily inserted in place between the clamping-arm and spring and with the same ease disengaged. The reins lie perfectly flat when held 60 by the device without roughening the edges of the rein or otherwise injuring them.

The spring E, as will be noticed, is simply bent around the extension c and not permanently attached thereto; hence the spring can 65 be removed by depressing the spring sufficiently to force it through the opening b, thereby replacing it with a new one. This is considered of importance, from the fact that springs of different strength may be used so as to adapt 70 them to reins of different thicknesses or shape; also, should the spring become broken or otherwise injured, a new one can be substituted.

If preferred, the U-spring C can be detached 75 from the yoke B and the latter used without it, the set-screws a acting as clamping-screws.

A device constructed as above described is both simple and durable, readily attached to the dash-board or other portions of a vehicle and detached when desired, without marring 80 or injuring the object to which it is attached, and the device can be manufactured and placed upon the market at a comparatively small cost, thereby bringing it within the reach of all requiring such a device.

Having now fully described my invention, which I claim as new, and desire to secure by Letters Patent, is—

1. In a driving-rein holder, the combination, with a suitable spring having a hooked end 90 and a slotted clamping-arm, of a bracket provided with an extension, said hooked end of the spring fitting over the same, whereby it is held to the bracket without the use of bolts or other fastenings and capable of ready removal 95 therefrom, substantially as and for the purpose set forth.

2. In a driving-rein holder, a bracket pro-

vided with a slotted claiming-arm, and a flat spring extending through the slot thereof and detachably connected to an extension of the bracket, in combination with means for securing said bracket to the dash-board or other portions of a vehicle, consisting of a yoke, a **U**-shaped spring located therein, and set-screws to increase the tension of the spring, substantially as and for the purpose specified.

In testimony that I claim the above I have to heretofore subscribed my name in the presence of two witnesses.

ABRAHAM COTTRELL.
